UNITED STATES PATENT OFFICE.

GUSTAV P. LAGEMANN, OF LUVERNE, MINNESOTA.

MILK-STRAINER ATTACHMENT.

Application filed July 21, 1923. Serial No. 653,049.

To all whom it may concern:

Be it known that I, GUSTAV P. LAGEMANN, a citizen of the United States, residing at Luverne, in the county of Rock and State 5 of Minnesota, have invented certain new and useful Improvements in Milk-Strainer Attachments, of which the following is a specification.

This invention relates to strainers and 10 supporting means therefor, and has for its primary object the provision, in a manner as hereinafter set forth, of a strainer which may be suspended entirely within the mouth of a receiving vessel.

15 Another object is the provision, in a manner as hereinafter set forth, of a strainer so constructed as to obviate the liability of an overflow through deposits of sediment upon the screen in the bottom thereof.

20 Another object of this invention is to provide a device of this character including a tubular body converging toward the foraminous discharge end and with means for suspending the body within a receptacle 25 and maintaining the same in vertical position therein.

Still another object is the provision of a 30 strainer and supporting means therefor, which will be strong, durable and inexpensive to manufacture.

The invention will be best understood from a consideration of the following detailed description taken in connection with the accompanying drawings forming part 35 of this specification, with the understanding that the invention is not confined to any strict conformity with the showing of the drawings, but may be changed and modified, so long as such changes and modifications mark no material departure from the 40 salient features of the invention as expressed in the appended claims.

In the drawings:—

Figure 1 is a side elevation of a portion 45 of a milk can, partly in section, and showing the device embodying this invention applied thereto.

Figure 2 is a top plan view of the invention.

50 Fig. 3 is a vertical transverse section of the same taken on the line 3—3 of Fig. 2, and

Fig. 4 is a view showing a modification of the attaching means.

55 Referring now to the drawings in detail, wherein like numerals of reference indicate

corresponding parts throughout the several views of the drawing, a portion of a milk can is shown at 1, having the upper part broken away to show the application of the 60 device embodying this invention. This device comprises a strainer body having an annular upper portion 2, a conoidal shaped intermediate portion 3 and a depending annular lower portion 4, of less diameter than the upper portion, preferably formed in one piece, although it is obvious that three sections may be fitted together to form the finished article.

65 A portion of the intermediate portion, extending from the lower edge of the upper portion to the upper edge of the lower portion, is removed and across the opening thus formed is secured a section of copper gauze screen 5, of the type commonly used in milk 70 strainers. The lower edge of this screen contacts with the usual straining screen 6, stretched across the lower part of the portion 3, at its juncture with the lower annular portion.

75 Provision is made for suspending the strainer in a can, by attaching to the upper portion 2, of the strainer, a plate member 7 of less width than length, and slightly curved transversely to conform to the curve 80 of the strainer, which plate is of sufficient length to contact with a goodly portion of the inner surface of the can neck, as shown in Fig. 1, and has its upper edge curved over to form a hook 8, which is positioned 85 over the edge of the neck of the can, as shown. Connection may be made between the support and strainer by rivets 9, or other suitable means.

90 In Fig. 4, is shown a modification of the supporting means for the strainer. Here a support is provided for the strainer which may be easily removed, should it be desirable to do so, and it comprises a frame preferably of wire, having two spaced leg members 10—10 which may be bent in appropriate places at 11 and 12, to conform to the shape of the funnel which they are to support. Each of the legs, at one end, is bent to provide hooks 13, which engage the lower edge of the funnel, and at a distance upward equal to the height of the funnel each leg is bent inward as at 14, downward and back upon itself as at 15, to form a hook, the back bent portion passing up and 100 back over the portion 14, and extended outward forming the horizontal portion 16,

where a down bend is made as at 17, to form a second hook 18, opposite the first. This second hook, like the first, is formed by bending the material back upon itself and as shown it passes up and along the under surface of 16, until it abuts 10, where it extends straight down, leaving 10 at 11, but continues down about half the length of the leg 10, when it is bent laterally to form the curved brace 19, which separates the two leg members and the two sets of hooks.

It will be seen from the above paragraph that a support may be had for any size strainer, which will be easily applied, and easily made to conform to the shape of the strainer body, by simply bending the legs 10, at the proper points, to fit the curves in the strainer. The portion 19, serves as a brace and support, as does 7, in the other form, the body of the strainer in both instances being held free from one side of the can neck and independent of the size of the neck.

Having thus described the invention, what is claimed as new is:—

1. A device of the class described, comprising a tubular body converging toward the discharge end and with a foraminous

closure at said discharge end, a supporting member attached to said body at its larger end and extended upwardly into a hook adapted to engage over the rim of a receptacle and extended downwardly and adapted to bear against the inner face of the adjacent wall of the receptacle, and thereby support the body in vertical position.

2. A device of the class described, comprising a tubular body converging toward the discharge end and with a foraminous closure at said discharge end and with a portion of one side of foraminous material merging into the foraminous closure, a supporting member attached to said body at its larger end and at the side opposite to the foraminous side portion, and extended upwardly into a hook adapted to engage over the rim of a receptacle and extended downwardly and adapted to bear against the inner face of the adjacent wall of the receptacle, and thereby support the body in vertical position and spaced from one wall of the receptacle.

In testimony whereof, I affix my signature hereto.

GUSTAV P. LAGEMANN.
